UNITED STATES PATENT OFFICE.

HENRY S. YOUNG, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed January 18, 1924. Serial No. 687,030.

My invention relates to railway traffic controlling apparatus, and particularly to apparatus for governing traffic at points where two or more tracks intersect or converge.

5 I will describe two forms of railway traffic controlling apparatus embodying my invention, and will then point out the novel features thereof in claims.

In the accompanying drawings Figs. 1^a, 1^b, 10 and 1^c when placed end to end in the order named constitute a diagrammatic view showing one form of my invention applied to two tracks crossed by a third track. Fig. 2 is a view showing a modification of the apparatus 15 shown in Figs. 1^a, 1^b, and 1^c as applied to the crossing of two tracks.

Similar reference characters refer to similar parts in each of the views.

Referring first to Figs. 1^a, 1^b, and 1^c, the 20 reference characters *a* and *b* designate two converging railway tracks which intersect just to the right of the limits of the drawing. Track *a* is divided, by means of insulated joints 1, into a plurality of successive track sections A—B, B—C, C—D, and D—E, and track *b* is divided by similar insulated joints 25 1 into a plurality of similar track sections F—G, G—J, J—K, and K—L. A third track *d* crosses the two tracks *a* and *b* at points 2 and 3 in sections C—D and J—K, respectively. 30 A track section O—Q in track *d* including crossings 2 and 3 is insulated from the rest of the track by means of insulated joints 1.

Each track section in each of the three 35 tracks *a*, *b* and *d*, is provided with a track circuit including a suitable source of energy such as a track battery connected across the rails adjacent one end of the section and designated by the reference character *N* with a distinguishing exponent. Connected across the 40 other end of each section is a track relay designated by the reference character *R* with a suitable exponent. Interposed between each track battery *N* and one rail of the associated 45 section is a resistance 4, one function of which is to limit the output of the battery when its terminals are short-circuited by the wheels and axles of a train.

It will thus be plain that each track section 50 is provided with a track circuit including a track battery *N*, a track relay *R*, a resistance 4, and the rails of the section, in series.

The track sections including crossings 2 and 3 are made electrically separate from each other but each is continuous throughout its 55 length. This is accomplished by means of insulated joints 1 adjacent the crossings and conductors around the joints in the usual manner.

Traffic from left to right over tracks *a* and *b* I will term "eastbound" traffic while I shall term traffic in the opposite direction over these tracks "westbound" traffic. In a similar manner, traffic moving from O toward Q on track *d* I shall call "northbound" traffic and 65 traffic in the opposite direction on this track I shall term "southbound" traffic.

Eastbound traffic on track *a* is governed by two trackway signals *S^B* and *S^C* located at points B and C, respectively. Westbound 70 traffic over this track is governed by signal *S^D* located at point D. Eastbound traffic over track *b* is governed by two signals located at points G and J, respectively, and designated by the reference character *S* with an exponent 75 corresponding to the location. Westbound traffic over track *b* is governed by a signal *S^K* located at point K. Northbound and southbound traffic over track *d* is governed by two indicators located at the lower and upper ends 80 respectively of section O—Q and designated by the reference characters *W* with exponents corresponding to the location. Signals *S^B* and *S^C* are three-position signals of any suitable form and are here shown as semaphore 85

signals each comprising a blade adapted to assume three positions at 0, 45 and 90 angular degrees with respect to the ground wherein the signal displays a stop, a caution, or a proceed indication, respectively. Each signal *S* 90 is also provided with an electric lamp 23 to provide night indications in accordance with the usual practice. Each signal *S* is supplied with energy from a suitable source such as a battery designated by the reference character 95 *Y* with an appropriate exponent. The indicators *W* may be of any suitable type and are each capable of assuming a proceed indication when energized and a stop indication when de-energized.

The supply of energy to each of the signals *S^B* and *S^C* from battery *Y* is controlled by the adjacent track relay and by a relay which for purposes of convenience I shall term a "jine" 100

relay and which is designated by the reference character M with an exponent corresponding to the associated signal. Referring particularly to signal S^G , this signal is biased to the stop indication and is provided with a caution circuit and a proceed circuit. The caution circuit passes from battery Y^G , through wire 7, front contact 8 of track relay R^G , wire 9, operating mechanism of signal S^G , wire 10, front contact 11 of track relay R^G , and wire 12 back to battery Y^G . This circuit is closed only when relay R^G is energized, under which condition signal S^G displays a caution indication. The proceed circuit passes from battery Y^G , through wire 7, front contact 8 of track relay R^G , wire 13, front contact 14 of line relay M^G , wire 15, operating mechanism of signal S^G , wire 10, front contact 11 of track relay R^G , and wire 12 back to battery Y^G . This circuit is closed only when relays R^G and M^G are both energized, under which conditions signal S^G displays a proceed indication. The circuit for relay M^G passes from battery Z^G located at point J, through wire 16, contact 17 operated by signal S^G , wire 18, front contact 19 of track relay R^G , wire 20, winding of relay M^G , and wire 21 and common wire 22 back to battery Z^G . It is clear that this circuit is closed only when signal S^G indicates proceed and relay R^G is energized. The circuit for lamp 23 of signal S^G passes from a lighting battery X^G , through wire 24, back contact 25 of track relay R^G , wire 26, lamp 23, wire 27, and back to battery X^G . It will be plain that this circuit is closed, and hence that lamp 23 is lighted, only when section F—G is occupied by a train.

The remaining signals S are similar to signals S^B and S^G but are capable of only two indications, "stop" and "proceed". Each of the signals S^C , S^D , S^J , and S^K is controlled by means of a line relay designated by the reference character H with an exponent corresponding to the location as follows: Referring particularly to signal S^J , when relay H^J is de-energized the bias of signal S^J causes the signal to display a stop indication but when this relay is energized a circuit is closed over which current flows from battery Y^J , through wire 28, front contact 29 of line relay H^J , wire 30, operating mechanism of signal S^J , wire 31, front contact 32 of relay H^J , and wire 33 back to battery Y^J . It will be evident, therefore, that signal S^J displays a proceed indication only when relay H^J is energized. The control of relay H^J will be explained in detail hereinafter. Interposed between track battery N^G and resistance 4 associated therewith is a relay r^G . The parts are so proportioned that when section G—J is unoccupied, the current through this relay is not great enough to energize the relay, but that when section G—J is occupied by a train, the current through relay r^G is increased, and this relay becomes energized. Lamp 23 of

signal S^J is provided with a circuit which passes from lighting battery X^J , through wire 34, lamp 23, wire 35, front contact 36 of relay r^G , and wire 37 back to battery X^J . It will thus be plain that lamp 23 of signal S^J is lighted only when section G—J, next in rear of the signal, is occupied. The control of signal S^C is similar to that of signal S^J . Relays H^D and H^K control signals S^D and S^K respectively in the same manner just explained in connection with signal S^J , but lamps 23 of signals S^D and S^K are controlled by track relays R^4 and R^8 respectively in the same manner as lamp 23 of signal S^G is controlled by track relay R^5 .

Section O—Q is provided with two derails 38 and 38^a located on opposite sides of the crossings 2 and 3 and arranged to cause derailment of trains approaching the crossings. Each derail is controlled by a device to which I will refer in general by the reference character V with an exponent corresponding to the location. For example, derail 38 is controlled by device V^Q in the following manner: A manually operable bar 39 capable of longitudinal motion is operably connected with the movable point of the derail 38 and to a pivoted locking sector 42. A locking armature 43 operated by a magnet 44 is arranged to co-operate with sector 42 so that when magnet 44 is de-energized the armature engages a shoulder on the sector and locks the derail in the open position. Two pivoted contact arms 40 and 41 are operated by bar 39 in such manner that when bar 39 is in its left-hand position, thus moving derail 38 to its normal or open position, normal contact 40—40^b is closed and reverse contact 41—41^b is open. When bar 39 is in its right-hand position, derail 38 is moved to its reverse or closed position, and normal contact 40—40^b is open and reverse contact 41—41^b is closed. It will be plain that if derail 38 is in the open position, it may be moved to the closed position only when magnet 44 is energized. Derail 38^a is controlled by a device V^Q in the same manner as just described for the control of derail 38 by device V^Q .

Magnets 44 of devices V^Q and V^Q are controlled in part by two auxiliary relays 5 and 6 as will be explained in detail hereinafter.

In addition to the relays already described, there are located at point K, two stick relays T^K and T^J associated with line relays H^K and H^J , respectively, a repeater relay P^G , and a relay U^G , which for purposes of explanation I shall term a repeater stick relay. In a similar manner, track a is provided, at point D, with two stick relays T^D and T^C , a repeater relay P^2 and a repeater stick relay U^2 .

Repeater relay P^G is energized over a circuit which passes from battery Z^G , through wires 45 and 46, front contact 47 of track relay R^5 , wire 48, front contact 49 of track relay R^6 , wire 130

50, winding of repeater relay P^6 , wire 51, front contact 52 of track relay R^7 , and wires 53 and 22 back to battery Z^G . Since this circuit includes front contacts on track relays R^5 , R^6 and R^7 , it is clear that relay P^6 is energized only when sections F—G, G—J and J—K are unoccupied. Relay P^2 is controlled in a similar manner by track relays R^1 , R^2 and R^3 .

Stick relay T^K is provided with a pick-up circuit which passes from battery Z^K , through wires 54 and 55, back contact 56 of track relay R^8 , wire 57, back contact 58 of track relay R^7 , wire 59, contact 60 operated by signal S^K , wires 61 and 62, winding of relay T^K , wire 63, back contact 64 of relay P^6 , and common wire 22 back to battery Z^K . It is plain that this circuit is closed only when signal S^K indicates proceed and relays R^7 , R^8 and P^6 are all de-energized. A stick circuit is provided for this relay over which energy passes from battery Z^K , through wire 54, front contact 65 of relay T^K , wires 66 and 62 and winding of relay T^K back to battery as before. It follows that after relay T^K is energized the stick circuit just traced is closed thus eliminating relays R^7 and R^8 and signal S^K from the control of relay T^K . Relay T^K thereafter remains in its energized condition as long as repeater relay P^6 is de-energized.

Stick relay T^J is provided with a pick-up circuit which passes from battery Z^J , through wires 16 and 16^a, contact 67 operated by signal S^J , wire 68, back contact 69 of track relay R^7 , wires 70 and 71, winding of relay T^J , wires 72 and 73, back contact 52 of relay R^7 , and wires 53 and 22 back to battery Z^J . This circuit is closed only when signal S^J indicates proceed and relay R^7 is de-energized. The stick circuit for relay T^J passes from battery Z^K , through wires 54 and 74, front contact 75 of relay T^J , wires 70 and 71, winding of relay T^J , wires 72 and 73, back contact 52 of track relay R^7 , and wires 53 and 22 back to battery Z^K . A branch is provided for this circuit which passes from wire 73, through back contact 76 of track relay R^8 , and wires 77, 82 and 22 back to battery Z^K . It follows that after relay T^J is energized, it is maintained in this condition over its own front contact as long as either relay R^7 or R^8 is de-energized.

The control of stick relays T^D and T^C associated with track a will be readily understood from the foregoing.

Stick repeater relay U^6 is provided with a pick-up circuit which passes from battery Z^K , through wire 54, front contact 78 of stick relay T^K , wires 79 and 80, winding of relay U^6 , and wires 81, 82 and 22 back to battery Z^K . This circuit is closed only when relay T^K is energized. Another circuit is provided for relay U^6 over which current flows from battery Z^K through wires 54, 55 and 83, front contact 84 of relay P^6 , wire 80, winding of relay U^6 , and wires 81, 82 and 22 back to battery Z^K . This circuit is closed only when relay P^6 is energized. The stick circuit for this relay passes from battery Z^D , through wires 85, 86 and 87, back contact 88 of relay U^2 , wires 89 and 80, winding of relay U^6 , and wires 81, 82 and 22 back to battery Z^D . This circuit is closed only when relay U^2 is de-energized. The pick-up circuit for stick repeater relay U^2 associated with track a is similar to that just traced for stick repeater relay U^6 , but the stick circuit for relay U^2 passes from battery Z^K , through wires 54 and 90, back contact 91 of stick repeater relay U^6 , wire 92, front contact 93 of stick repeater relay U^2 , wires 94, 95 and 96, winding of relay U^2 , and wire 22 back to battery Z^K . It is plain that this circuit is closed only when relay U^2 is already energized and relay U^6 is de-energized.

Line relay H^K for track b is provided with a circuit which may be traced from battery Z^D , through wires 85 and 97, normal contact 40^a—40 of device V^a , wire 98, normal contact 40^a—40 of device V^o , wire 99, front contact 100 of track relay R^9 , wires 101 and 102, front contact 103 of track relay R^7 , wires 104 and 105, front contact 106 of repeater relay P^6 , wire 107, winding of relay H^K , and wires 108 and 22 back to battery Z^D . It follows that relay H^K is energized only when derails 38 and 38^a are both set in the derailing position and track relays R^9 and R^7 and repeater relay P^6 are all energized. The control of relay H^D associated with track a is similar to that just described for relay H^K .

Current is supplied to relay H^J over a circuit which passes from battery Z^D , through wires 85 and 97, normal contact 40^a—40 of device V^a , wire 98, normal contact 40^a—40 of device V^o , wire 99 front contact 100 of track relay R^9 , wires 101 and 102, front contact 103 of track relay R^7 , wire 104, front contact 109 of track relay R^8 , wire 110, back contact 111 of stick repeater relay U^6 , wire 112, back contact 113 of stick relay T^K , wire 114, front contact 115 of stick repeater relay U^2 , wire 116, winding of relay H^5 , and wires 117 and 22 back to battery Z^D . It follows that relay H^J will be energized only when derails 38 and 38^a are in the derailing positions, track relays R^7 , R^8 and R^9 and stick repeater relay U^2 are energized and stick relay T^K and stick repeater relay U^6 are de-energized. The control of relay H^C is similar to the control of relay H^J and will be readily understood from the foregoing.

Relay 5 adjacent point O is provided with a circuit which passes from battery Z^B , through wire 118, contact 119 operated by signal S^B , wire 120, contact 121 operated by signal S^C , wire 122, back contact 123 of track relay R^9 , wire 124, winding of relay 5, and wires 125 and 22 back to battery Z^B . This circuit is closed only when signal S^B is displaying a stop or a caution indication, signal S^C is displaying a stop indication, and track

relay R^9 is de-energized. In a similar manner relay 6 is controlled by signals S^G and S^J and track relay R^9 over a circuit which passes from battery Z^G , through wire 45, contact 126 controlled by signal S^G , wire 127, contact 128 operated by signal S^J , wire 129, back contact 130 of track relay R^9 , wire 131, winding of relay 6, and wires 132, 133 and 22, back to battery Z^G .

10 Indicators W associated with track d are provided with a circuit as follows: from battery Z^K , through wires 54 and 55, front contact 56 of track relay R^8 , wires 134 and 135, front contact 136 of track relay R^7 , wire 137, front contact 138 of repeater relay P^6 , wires 139 and 140, front contact 141 of repeater relay P^2 , wires 142 and 143, front contact 144 of track relay R^3 , wires 145 and 146, front contact 147 of track relay R^4 , wire 148, indicator W^0 , wire 149, indicator W^0 , and wires 133 and 22 back to battery Z^K . This circuit is closed therefore only when track relays R^3 , R^4 , R^7 and R^8 and repeater relays P^2 and P^6 are all energized. The circuit is provided with a number of branches, one of which passes from wire 54, through wire 74, front contact 150 of stick relay T^J , and wire 151 back to wire 135. It will thus be seen that when stick relay T^J is energized, track relay R^8 is removed from the control of the indicators W. Another branch is provided over which current flows from wire 137, through wire 152, front contact 153 of stick relay T^K , and wire 154 back to wire 139. The energization of relay T^K , then, removes relay P^6 from the control of the indicators W. When relay T^D is energized a branch is closed around the contact 141 of relay P^2 and current then flows directly from wire 139, over front contact 155 of relay T^P , to wire 142. Still another branch passes from wire 145, through front contact 156 of relay T^C , and wire 157, to wire 148. It is plain that the energization of relay T^C thus eliminates relay R^4 from the control of the indicators.

50 Current is supplied to magnets 44 of devices V^Q and V^0 over the circuit just traced for indicators W from battery Z^K as far as wire 148, and thence over wire 158, contact 159 operated by signal S^D , wire 160, contact 161 operated by signal S^K , wire 162, front contact 163 of relay 6, wire 164, front contact 165 of relay 5, wire 166, magnet 44 of device V^0 , wire 167, magnet 44 of device V^Q , and wires 168 and 22 back to battery Z^K . It is thus plain that the circuit from wire 148 through the locking magnet 44 is closed only when signals S^D and S^K are both at stop, and relays 5 and 6 are both energized.

55 In addition to the circuit just traced a second circuit is provided, passing from battery Z^D , through wires 85 and 169, reverse contact 41^b—41 of device V^Q , wires 170 and 166, magnet 44 of device V^0 , wire 167, magnet 44 of device V^Q , and wires 168 and 22 back to

battery Z^D . Another circuit passes from battery Z^D , through wire 85, reverse contact 41^b—41 of device V^0 , wires 171 and 166, magnet 44 of device V^0 , wire 167, magnet 44 of device V^Q , and wires 168 and 22 back to battery Z^D . It is therefore clear that when one device V is in the reverse position both devices V are unlocked irrespective of the condition of the other apparatus.

60 I will now explain the operation of the apparatus as a whole.

As shown in the drawing, the apparatus is in the position corresponding to the unoccupied condition of the track. Under these conditions all track relays R are energized, repeater relays P^6 and P^2 are both energized, and therefore stick repeater relays U^6 and U^2 are energized. Line relays H associated with signals S^P and S^K are both energized and these signals are therefore indicating proceed, whereas line relays H associated with signals S^J and S^C are de-energized causing these signals to display stop indications and line relays M associated with signals S^B and S^G are also de-energized. Signals S^G and S^B therefore display caution indication. Relays r are all de-energized. The lamp 23 associated with each of the signals S is extinguished. Relays 5 and 6 have their circuits open at back contacts on track relay R^9 and therefore these relays are de-energized. As a result, locking magnets 44 of devices V^0 and V^Q are de-energized and derails 38 and 38^a are locked in the normal, or derailing position. Stick relays T are all de-energized and indicators W associated with section O—Q are energized and indicate proceed.

65 I will now assume that an eastbound train moves along track b. As this train enters section F—G, track relay R^5 becomes de-energized, thus lighting lamp 23 associated with signal S^G and opening the circuit for repeater relay P^6 which thereupon becomes de-energized. The opening of front contact 84 of repeater relay P^6 opens one circuit for relay U^6 . The other circuits for this relay are already open, one at front contact 78 of relay T^K and the other at back contact 88 of relay U^2 . Relay U^6 is therefore de-energized. The closing of back contact 111 of relay U^6 completes the circuit for relay H^J . The energization of relay H^J closes, at front contacts 29 and 32 thereon, the proceed circuit for signal S^J , and this signal therefore displays a proceed indication. The closing of contact 17 in response to the movement of signal S^J to the proceed position causes relay M^G to become energized, thus moving signal S^G to the proceed position by completing the proceed circuit for this signal at front contact 14 on relay M^G . The train is therefore allowed to proceed along track b. The de-energization of relay P^6 causes, by the opening of front contact 106 thereon, the interruption of the proceed circuit for signal S^K , which sig-

nal now displays a stop indication. Lamp 23 associated with the signal is not lighted, however since track relay R^8 is energized. The entrance of a westbound train into section 5 $K-L$ would immediately light this lamp and the train would be brought to a stop at point K . It should also be noted that the opening of contact 138 on relay P^6 de-energizes indicators W so that these indicators assume the 10 stop position.

Referring again to the eastbound train now occupying section $F-G$, when this train proceeds into section $G-J$ the track relay R^6 will become de-energized. As the train 15 leaves section $F-G$, track relay R^5 becomes energized thus extinguishing lamp 23 of signal S^G , but the circuit for relay P^6 is now broken at front contact 49 of track relay R^6 and therefore the apparatus controlled by 20 relay P^6 suffers no change although contact 47 of relay R^5 is closed. Due to the de-energization of relay R^6 , relay M^G is also de-energized and signal S^G now displays a stop indication. The entrance of the train into section 25 $G-J$ also causes relay R^6 to become energized and closes the circuit for lamp 23 of signal S^J . As the train enters section $J-K$, track relay R^7 is shunted and de-energized. Repeater relay P^6 is still de-energized, therefore, 30 its circuit now being broken at front contact 52 of relay R^7 . The circuit for line relay H^J is now interrupted however, at front contact 103 of relay R^7 . A brief interval elapses before signal S^J moves to the stop position however and during this interval the closing of back contacts 52 and 69 of relay R^7 completes the pick-up circuit for stick relay 35 T^J over contact 67 operated by signal S^J . Relay T^J is maintained in its energized condition after signal S^J goes to stop, over its own front contact 75 and back contact 52 of relay R^7 , as long as the train occupies section $J-K$. Now as the train proceeds into section $K-L$, the de-energization of track relay R^8 closes 40 another stick circuit for relay T^J which includes back contact 76 of relay R^8 but not back contact 52 of relay R^7 , and relay T^J therefore is maintained in its energized condition by the latter circuit till the train leaves 45 section $K-L$. When the train passes out of section $J-K$, repeater relay P^6 is energized again over front contacts of track relays R^5 , R^6 and R^7 , now energized, and relay P^6 in turn closes the circuit for relay U^6 . When 50 the train leaves section $K-L$, the resulting energization of relay R^8 restores the circuits to their normal condition by de-energizing relay T^J . It should be pointed out that as the train leaves section $G-J$, the picking up 55 of relay R^6 moves signal S^G to caution, which signal stays in this position till the train leaves section $K-L$. It should also be noted that with the eastbound train in section $K-L$ indicators W are energized and indicate proceed on account of front contact 150 on stick

relay T^J shunting around front contact 56 on track relay R^8 .

The operation of the apparatus as an eastbound train moves over track a will be readily understood from the foregoing. 70

I will now assume that a westbound train enters section $K-L$ of track b . Track relay R^8 is de-energized thus lighting lamp 23 of signal S^K but otherwise the apparatus is not affected. Relay H^K being energized, signal S^K continues to indicate proceed. As the train enters section $J-K$, relay R^7 is de-energized, which in turn de-energizes relay P^6 . As a result line relay H^K is de-energized, thus interrupting the proceed circuit for signal S^K . A brief interval elapses before this signal moves from the proceed position, however, and during this interval a pick-up circuit is closed for stick relay T^K over contact 60 operated by signal S^K , and back contact 58 of relay R^7 . Relay T^K is maintained in its energized condition after the opening of contact 60, over a stick circuit including its own front contact 65. This stick circuit is controlled also by back contact 64 of repeater relay P^6 , and stick relay T^K will therefore remain energized till the train passes beyond point F . 85

As the train passes through sections $G-J$ and $F-G$, the track relays R^6 and R^5 are successively de-energized. While the train is in these sections, indicators W indicate proceed and signal S^J is held at stop on account of relay T^K being energized. After the train leaves section $F-G$, all the track relays are 90 energized, relay P^6 is energized, and the circuits are restored to normal by the closing of relay H^K and the opening of relay T^K . 95

Westbound traffic over track a operates the apparatus associated therewith in the same manner as just described in connection with track b . 100

I will now assume that a northbound train is moving over track d . As this train moves into section $O-Q$, indicator W^0 being at proceed, track relay R^9 becomes de-energized, thus completing the circuits for relays 5 and 6 over its back contacts, and causing relays H^D and H^K to become de-energized and holding relays H^C and H^J de-energized thus moving signals S^D and S^K to stop and holding signals S^C and S^J at stop. The closing of front contacts 163 and 165 on relays 6 and 5 respectively, completes the circuit for electric locking magnet 44 on devices V^0 and V^9 . These devices are therefore unlocked and may then be reversed to move the associated derails 110 38^a and 38 into the non-derailing position. It should be mentioned that devices V^0 and V^9 may be mounted at points remote from the trackway, as in an interlocking cabin. The derails having been reversed, the train 115 may proceed through section $O-Q$. After the train has left section $O-Q$, the devices V may be reversed at any time. Relay R^9 hav- 120

125

130

ing become energized after the train left section O—Q, the restoring of derails 38 and 38^a returns the circuits to their normal condition.

5 Southbound traffic over section O—Q is controlled in the same manner as just explained for traffic in the opposite direction.

I will now explain how traffic on one track is protected from collision with traffic on another track.

10 I will first assume that an eastbound train is proceeding on each of the tracks *a* and *b*. Since the tracks *a* and *b* converge toward the right and intersect just beyond the right hand 15 limits of the drawing it is desirable to stop one train but to permit the other to proceed. This is accomplished by carrying the control of line relay H^J, which governs signal S^J, over front contact 115 of relay U² and back 20 contact 111 of relay U⁶, and by carrying the control of line relay H^c, which governs signal S^c, over a front contact 173 of relay U⁶ and back contact 172 of relay U². I have already 25 explained how a train passing from west to east over track *a* or *b* causes the de-energization of relay U associated therewith. If two 30 eastbound trains are approaching the crossing one on track *a* and one on track *b*, and the train on track *a* is the first to enter the stretch 35 of track shown in the drawing, relay U² is de-energized and a stick circuit is closed over which relay U⁶ is maintained in its energized condition. The circuit for relay H^J is therefore held open and signal S^J is held at stop 40 and will not clear till the eastbound train on track *a* has passed signal S^D. Similarly, if the train on track *b* is the first to enter the stretch, a train on track *a* is held at signal S^c till the train on track *b* clears signal S^K.

45 40 If eastbound trains should enter sections A—B and F—G at exactly the same instant, both relays U² and U⁶ would be de-energized, but relay U⁶ would immediately pick up again, its circuit being completed over back contact 88 of relay U². The train on track *a* would be allowed to proceed and the train on track *b* would be stopped till the train on track *a* cleared section C—D.

50 I will next assume that a train, moving in either direction over track *d* approaches section O—Q. I will also assume that an eastbound train is moving toward crossing 3 over section F—G. As explained hereinbefore, relay P⁶ is deenergized by the eastbound train and signal S^K indicates stop. The circuit for indicators W is open at front contact 138 of relay P⁶, and the branch around this contact 55 through front contact 153 of relay T^K is also open and the indicators both are at stop. As the train on track *b* proceeds into section J—K, track relay R⁷ will be de-energized and stick relay T^J will become energized. The circuit for indicators W is now further 60 broken at front contact 136 of track relay R⁷. 65 Not until the eastbound train clears section

J—K will the energization of relays P⁶, T^J and R⁷ complete the circuit for indicators W which will then indicate proceed to inform the operator of a train traversing track *d* that he may proceed through section O—Q. 70 If the train on track *d* attempts to pass either indicator it will be forced to stop or be thrown from the track by one of the derails 38 or 38^a since neither device V can be operated while an eastbound train occupies any portion 75 of track *b* between points F and K, the circuit for magnets 44 of devices V then being open at front contact 138 of relay P⁶.

If a train is proceeding in either direction over track *d*, and only one of the devices V 80 has been reversed when a train approaches the crossing over track *a* or *b*, this second train will be stopped at the first signal, but the remaining device V can still be reversed, its lock being energized over a reverse contact 85 41—41^b of the other device V.

If a train attempts to pass through section O—Q while track *b* is occupied by a westbound train the operation of the apparatus is as follows: As soon as the westbound train passes point L, the circuit for indicators W is opened at front contact 56 of relay R⁸, and, the branch around this contact through front contact 150 of relay T^J being already open, these indicators each display a stop indication. When the train proceeds into section J—K, relay R⁷ is opened and interrupts the indicator circuit at front contact 136 thereon. At the same time stick relay T^K is energized and closes a shunt 100 around contact 138 of relay P⁶ now de-energized. When the train passes out of section K—L, relay R⁸ picks up and as the train passes out of section J—K, the resulting energization of relay R⁷ completes the circuit 105 for indicators W which then clear the cross track O—Q. Even if a train on track O—Q should pass the indicator W when indicating stop as explained above, the derails could not be moved till the train on track *b* cleared 110 point J, since the energy for magnets 44 of device V passes over the same circuit as the energy for indicators W from battery Z^K to wire 148 and I have just explained how this circuit is interrupted by the passage of 115 a westbound train through sections J—K and K—L.

It will be clear from the drawing that trains on track *d* are protected when track *a* is occupied by trains in either direction in 120 the same manner as just described in connection with trains on track *b*.

Finally, I will assume that a train occupies section O—Q. I have already explained that when relay R⁹ is de-energized, the opening of front contact 100 thereon opens the circuit for relay H^c, H^D, H^J and H^K. Signals S^D and S^K are therefore moved to the stop position, and signals S^c and S^J are held in that position. It will be noted that all 130

these signals must be at stop before the derails can be reversed to allow the train on track *d* to negotiate crossings 2 and 3 and therefore complete protection is obtained for 5 trains on track *d* from trains on tracks *a* and *b* since to approach either crossing under these conditions a westbound or an eastbound train must pass a stop signal. The circuits are restored to normal as soon as the derails 10 are returned to their normal or derailing condition, and the train has cleared section O—Q.

One feature of my invention is that when 15 a train on one of two intersecting tracks approaches the crossing from either direction, the traffic governing apparatus associated with the other track assumes its more restrictive condition when the train is at a comparatively large distance from the crossing 20 but may be returned to the less restrictive condition after the train has receded a comparatively short distance from the crossing.

Referring now to Fig. 2, I show only two stretches of single track railway *a* and *d*, 25 intersecting in a crossing 2. Track *a* is divided as before by means of insulated joints into sections B—C, C—D, and D—E, and track *d* is similarly divided into sections Y—O, O—Q, and Q—Z. The crossing 2 is 30 insulated from sections C—D and O—Q by means of insulated joints 1, but the rails of these sections are made electrically continuous around the crossing with suitable conductors.

35 Eastbound traffic over track *a* is controlled by signal S^c , westbound traffic over this stretch by signal S^d , northbound traffic over track *d* is controlled by signal S^o , and southbound traffic by signal S^q . These signals are 40 similar to signals S^c , S^d , S^j and S^k of Fig. 1 except that the light 23 of each such signal in Fig. 2 is constantly energized and is omitted from the drawing for the purpose of 45 simplicity. The control of signals S will be explained hereinafter.

Each of the track sections of each track *a* and *d* is provided, as before, with a track circuit including a track battery N , an impedance 4, the rails of the section and the 50 winding of a track relay R in series. Track *a* is also provided with a siding having a switch 270 associated with section B—C. Two circuit controllers 252 and 251 are operatively connected with switch 270 so that 55 when this switch is in such position as to permit movements of traffic along track *a* circuit controller 252 is closed and circuit controller 251 is open. When switch 270 is reversed to permit traffic movements from track *a* 60 into siding *g* or vice-versa, circuit controller 252 is open, circuit controller 251 is closed. The purpose and function of these two circuit controllers will appear as the explanation proceeds. Siding *g* is provided with a

track circuit comprising a track relay R^{15} , 65 an impedance 4, and a track battery N^{15} .

Each of the signals S controls a relay designated by the reference character k with an appropriate exponent. For purposes of explanation I shall hereinafter refer to these 70 relays as "signal" relays. Each of these relays k is arranged to be energized when the corresponding signal indicates stop. Referring for example to relay k^c , the circuit for this relay passes from one terminal of a suitable source of energy such as a battery 174, through wires 175 and 176, circuit controller 177 operated by signal S^c , wire 178, winding of relay k^c , and wires 179, 180, 181 and 182 back to battery 174. The control of each of 80 the remaining signal relays k by the corresponding signals S is similar to the control of relay k^c by signal S^c .

There are also provided certain repeater 85 relays which are designated by the reference character P with appropriate exponents. Referring first to repeater relay P^2 the circuit for this relay passes from battery 174, through wires 175, 186 and 187, front contact 188 of track relay R^2 , wire 189, winding 90 of repeater relay P^2 , wires 190, 181 and 182 back to battery 174. It will be plain that this repeater relay P^2 is energized only when track relay R^2 is energized. Repeater relays 95 P^o , P^3 , P^{10} and P^{11} are controlled in exactly the same manner by track relays R^o , R^3 , R^{10} and R^{11} , respectively.

An auxiliary stick relay designated by the reference character t with a suitable exponent 100 is associated with each of the track relays R^{15} and R' . The control of these auxiliary stick relays will be explained in detail hereinafter. The circuit for repeater relay P' may be traced from battery 174 through 105 wires 175, 186 and 187, front contact 193 of auxiliary stick relay t' , wire 194, winding of repeater relay P' , and wires 195, 181 and 182, back to battery 174. It follows that repeater relay P' is energized only when auxiliary 110 stick relay t' is energized.

There are also provided certain stick relays designated by the reference character T with distinguishing exponents. Referring particularly to relay T^c , this relay is provided 115 with a pick-up circuit which passes from a suitable source of energy such as battery 196, through wires 197, 198 and 199, back contact 200 of signal relay k^c , wire 201, back contact 202 of repeater relay P^2 , wire 203, winding of stick relay T^c , and wires 204, 120 181 and 205 back to battery 196. It will be clear that this pick-up circuit is closed only when relay P^2 , and therefore relay R^2 , is de-energized, and relay k^c is de-energized. Stick relay T^c is also provided 125 with a stick circuit over which current flows from battery 196, through wires 197, 258 and 206, back contact 207 of repeater

relay P^2 , wires 208 and 209, front contact 210 of stick relay T^c , wire 211, winding of relay T^c , and wires 204, 181 and 205 back to battery 196. A second stick circuit is provided for this relay which may be traced from battery 196, through wires 197 and 213, back contact 214 of repeater relay P^3 , wire 209, front contact 210 of relay T^c , wire 211, winding of relay T^c , and wires 204, 181 and 205 back to battery 196. Stick relay T^0 is provided with a pick-up circuit controlled by repeater relay P^0 and signal relay k^0 and stick circuits controlled by relays P^9 and P^{11} , which circuits are similar to those just traced for relay T^c . Stick relay T^D is provided with a pick-up circuit which passes from battery 196, through wires 197 and 198, back contact 216 of signal relay k^D , wire 217, back contact 218 of repeater relay P^2 , wires 219 and 220, winding of stick relay T^D , and wires 221, 181 and 205, back to battery 196. One stick circuit for relay T^D passes from battery 196, through wires 197 and 223, back contact 224 of repeater relay P' , wires 225 and 226, front contact 227 of relay T^D , wires 219 and 220, winding of relay T^D , and wires 221, 181 and 205, back to battery 196. The second stick circuit for relay T^D passes from battery 196 over wires 197 and 258, back contact 228 of repeater relay P^2 , wires 229 and 226, front contact 227 of relay T^D , wires 219 and 220, winding of relay T^D , and wires 221, 181 and 205 back to battery 196. The pick-up circuit for stick relay T^{11} passes from battery 196 through wires 197, 198, 230 and 231, back contact 232 of relay P^{11} , wire 233, back contact 234 of repeater relay P^0 , wires 235 and 236, winding of relay T^{11} and wires 237, 181 and 205 back to battery 196. When repeater relay P^0 is de-energized and stick relay T^{11} is already energized from its pick-up circuit, a stick circuit is closed for relay T^{11} over which this relay is maintained in its energized condition by current which flows from battery 196 through wires 197 and 242, back contact 243 of relay P^0 , wires 239 and 240, front contact 241 of stick relay T^{11} , wires 235 and 236, winding of relay T^{11} , and wires 237, 181 and 205 back to battery 196. A second stick circuit for relay T^{11} supplies current from battery 196 through wire 197, back contact 238 of relay P^0 , wires 239 and 240, front contact 241 of relay T^{11} , wires 235 and 236, windings of relay T^{11} and wires 237, 181 and 205 back to battery 196.

The reference character f designates a directional stick relay controlled in the following manner: When relays P' and P^3 are energized, directional stick relay f is energized by current which flows from battery 196, through wires 197 and 223, front contact 244 of relay P' , wire 245, front contact 247 of relay P^3 , wire 248, winding of relay f and wires 249, 181 and 205 back to battery 196. This relay is provided with another circuit passing from battery 196, through wires 197, 198 and 246, front contact 259 of stick relay T^P , wires 260, 254, 254^a and 245, front contact 247 of relay P^3 , wire 248, winding of relay f , wires 249, 181 and 205 back to battery 196. Still another circuit is provided which may be traced from battery 174, through wires 175 and 250, circuit controller 251 operated by switch 270 of siding g , wires 261, 254, 254^a and 245, front contact 247 of relay P^3 , wire 248, winding of relay f and wires 249, 181 and 182, back to battery 174. Each of these three circuits is provided with a branch which passes from wire 254, through wire 255, front contact 256 of relay T^c and wire 257 back to wire 248. It follows that when relay T^c is energized, relay P^3 is removed from the control of directional stick relay f . A stick circuit is also provided for relay f over which current flows from battery 196, through wires 197, 198 and 262, back contact 263 of relay k^0 , wires 264 and 265, front contact 266 of relay f , wire 267, winding of relay f and wires 249, 181 and 205, back to battery 196. This circuit is provided with a branch which passes from wire 198, through wire 268, back contact 269 of relay k^0 , and wire 269^a, back to wire 265. It is therefore clear that having once been energized relay f is subsequently maintained in its energized condition as long as either relay k^0 or k^0 is de-energized.

Auxiliary stick relay t' is provided with a pick-up circuit which passes from battery 174, through wires 175, 186, 187 and 191, front contact 271 of track relay R' , wire 272, front contact 273 of track relay R^{15} , wires 274 and 275, winding of relay t' , and wires 276, 181 and 182 back to battery 174. This circuit is, of course, closed only when relays R' and R^{15} are both energized. When relay t' is energized, and relay R' is also energized, a stick circuit is closed for relay t' over which relay t' is held in its energized position by current which flows from battery 174, through wires 175, 186, 187 and 191, front contact 271 of track relay R' , wires 272, 283 and 278, front contact 279 of relay t' , wires 280 and 275, winding of relay t' , and wires 276, 181 and 182 back to battery 174. This stick circuit is provided with a branch which passes from wire 186, through wire 281, back contact 282 of auxiliary stick relay t^{15} , and back to wire 283. It follows that when relay t^{15} is de-energized, relay R' is removed from the control of the stick circuit for relay t' . Relay t^{15} is provided with a pick-up circuit and with stick circuits similar to those just described for relay t' and in addition is provided with a second pick-up circuit which passes from battery 174, through wires 175, 186, 281 and 284, front contact 285 of relay

R^{15} , wires 286 and 287, a manually operable circuit controller 288, wires 289, 290 and 291, winding of relay t^{15} , and wires 181 and 182 back to battery 174. Circuit controller 288 is located at some convenient place along the trackway so as to be accessible to a trainman.

The trackway signals S are controlled in the following manner: Referring particularly to signal S^c , this signal is controlled by 10 a circuit which passes from battery 174 through wire 175, circuit controller 252 operated by switch 270 of siding g , wire 292, front contact 293 of track relay R^{15} , wire 294, front contact 295 of track relay R^2 , wire 296, 15 front contact 297 of repeater relay P^9 , wire 298, front contact 299 of signal relay k^o , wire 300, front contact 301 of signal relay k^o , wire 302, back contact 303 of directional stick relay f , wires 304 and 313, front contact 353 20 of signal relay k^o , wire 305, front contact 306 of repeater relay P^3 , wire 307, back contact 308 of repeater relay P' , wire 309, back contact 310 of stick relay T^o , wire 311, operating mechanism of signal S^c , and wire 312 back 25 to battery 174. The circuit for signal S^p is the same as that just traced for signal S^c as far as wire 304, and the circuit for signal S^p passes thence through wire 313, front contact 314 of signal relay k^o , wire 315, front contact 316 of repeater relay P' , wire 317, back contact 318 of repeater relay P^s , wire 319, back contact 320 of stick relay T^c , wire 321, operating mechanism of signal S^p , and wires 322, 30 181 and 182, back to battery 174. A circuit is 35 provided for signal S^o over which current flows from battery 196 through wires 197 and 323, front contact 324 of repeater relay P^o , wire 325, front contact 326 of repeater relay P^2 , wire 327, front contact 328 of signal relay k^c , wire 329, front contact 330 of signal relay k^p , wire 331, front contact 332 of directional stick relay f , wires 333 and 334, front contact 335 of signal relay k^o , wire 336, front contact 337 of repeater relay P^{11} , wire 338, back contact 339 of repeater relay P^{10} , wire 340, back contact 341 of stick relay T^{11} , wire 342, operating mechanism of signal S^o , and wires 181 and 205 back to battery 196. The circuit for signal S^q is the same as that just traced for 40 signal relay S^o as far as wire 333, the circuit for signal S^q passing from this wire through wire 343, front contact 344 of signal relay k^o , wire 345, front contact 346 of repeater relay P^{10} , wire 347, back contact 348 of repeater relay P^{11} , wire 349, back contact 350 of stick relay T^o , wire 351, operating mechanism of signal S^q , wires 352a, 352, 181 and 205 back to battery 196.

As shown in the drawing all of the parts of the apparatus are in the positions corresponding to the unoccupied condition of the track and switch 270 is in the normal position, that is, in such a position as to permit movements of traffic along track a . Under these conditions all track relays R are ener-

gized, all repeater relays P , all signal relays k and stick relays t^{15} and t' and directional stick relay f are also energized. Stick relays T^c , T^o , T^p and T^{11} are however de-energized, and signals S^c , S^p , S^o and S^q all indicate stop. 70

In explaining the operation of the apparatus I will first assume that a northbound train prepares to negotiate the crossing 2. As the train enters section $Y-O$ track relay R^{10} is de-energized, thus de-energizing repeater relay P^{10} and completing the circuit for signal S^o , which signal indicates thereupon proceed. Signal relay k^o is therefore de-energized. As the train enters section $O-Q$ relay R^o is de-energized, thus de-energizing repeater relay P^o . The de-energization of relay P^o opens, at front contact 324 thereon, the operating circuit for signal S^o and this signal thereupon indicates stop. After the closing of contact 80 355 of relay P^o and prior to the re-energization of relay k^o , resulting from the movement of signal S^o to the stop position, the pick-up circuit for relay T^o is closed, thus energizing this relay and the relay is subsequently maintained in its energized condition over its own 85 front contact and a back contact on relay P^o as long as the train occupies any portion of section $O-Q$. As the train proceeds into section $Q-Z$ relays R^{11} and P^{11} are de-energizing thus completing a branch for the stick circuit 90 of relay T^o and eliminating relay P^o from the control of relay T^o . As the train moves out of section $O-G$, relays R^o and P^o become energized. As the train moves out of section 95 $Q-Z$ the energization of relay R^{11} , of course, picks up relay P^{11} , which in turn de-energizes relay T^o , thus restoring the apparatus to the normal condition. It should be noted that with the northbound train in section $Q-Z$ relay T^o is held energized and the operating circuit for signal S^q is open at back contact 350 on relay T^o . Signal S^q is held at stop 100 while the northbound train is receding from crossing so that signal S^c or S^p may clear for a train on track a . The operation of the apparatus as a train moves from north to south through track d is the same as that just described for a northbound train and will be understood without further explanation. 105

I will now assume that a train moving from left to right proceeds toward the crossing. As the train enters section $B-C$, relay R' becomes de-energized, thus de-energizing auxiliary stick relay t' , which in turn de-energizes repeater relay P' . Relay f thereupon becomes de-energized. The closing of back contact 303 of relay f and the closing of back contact 308 of relay P' complete the circuit 110 for signal S^c which thereupon moves to the proceed position. As a result the circuit for relay k^c is opened at circuit controller 177 and this relay becomes de-energized. As the train enters section $C-D$, relays R^2 and P^2 are de-energized and the circuit for signal S^c 115 is opened at front contact 295 of track relay 120 R^2 . As the train moves out of section $C-D$ the circuit for signal S^c is closed at front contact 295 of track relay 125 R^2 . As the train moves out of section $D-Z$ the circuit for signal S^c is opened at front contact 295 of track relay 130 R^2 .

R². Signal S^c therefore starts to move to the stop position and the circuit for relay k^c will again be closed. The closing of back contact 202 of relay P² closes the pick-up 5 circuit for relay T^c for a brief interval however, before relay k^c becomes energized, thus energizing relay T^c which remains thereafter in its energized condition, by virtue of its stick circuit including back contact 207 of relay P². As the train enters section D—E, the de-energization of relay R³ opens the 10 circuit for relay P³ and removes relay P² from the control of relay T^c by closing a branch around contact 207 of relay P². Relay 15 T^c therefore remains energized after the train moves out of section C—D although this movement allows relays R² and P² to become energized. As the train clears section B—C, the energization of relay R' again energizes 20 relay t' and hence relay P'. Relay f then becomes energized. As the train moves out of section D—E, relays R³ and P³ become energized, thus de-energizing relay T^c and restoring the apparatus to the normal condition. The operation of the apparatus for 25 westbound traffic over track a will be readily understood from the drawing.

I will now assume that a southbound train on track d has moved into section Q—Z, thus 30 de-energizing relays R¹¹ and P¹¹, and causing signal S^o to display a proceed indication. If, now, a northbound train enters section Y—O, relays R¹⁰ and P¹⁰ are de-energized, but the circuit for signal S^o is now broken 35 at front contact 337 of repeater relay P¹¹ and signal S^o can not clear. The entrance of this train into section Y—O will, however, open the circuit for signal S^o and thus prevent a head-on collision by displaying a stop indication to both trains.

If a southbound train occupies section Q—Z, and an eastbound train on track a approaches the crossing 2, relays R', t', and P' are de-energized as the latter train enters 40 section B—C. The circuit for signal S^c is now open at front contact 337 of relay P¹¹ and the signal therefore continues to indicate stop. As the train on track d enters section O—Q the de-energization of relay P⁹ 45 opens the circuit for signal S^c at front contact 324 of relay P⁹. When the train clears section Q—Z, allowing relays R¹¹ and P¹¹ to close, signal S^c still remains at stop. As the train on track d clears section C—Q, the circuit for signal S^c is completed over front 50 contact 324 of relay P⁹ and signal S^c then indicates proceed to allow the train on track a to negotiate the crossing. If an eastbound train occupies section B—C, the de-energization 55 of relay f, prevents the clearing of signals S^o or S^o till the train moves out of section C—D. The operation of the apparatus when a train is approaching the crossing from other directions will be understood from 60 the foregoing and it will thus be seen that

a train approaching the crossing from any direction opens the circuits for the signals governing all conflicting routes, as soon as the train enters the section in advance of the crossing, and allows the signal for conflicting 70 routes to be cleared as soon as the train moves out of the section containing the crossing. Further protection is afforded by carrying the control of each signal over a front contact of each of the signal relays for all conflicting signals thus insuring that only one signal can be cleared at a time. 75

I will now assume that switch 270 is reversed, that is, that this switch is in a position to allow traffic movements between section B—C and siding g. The closing of circuit controller 251 removes relay P' from the control of relay f and relay f therefore, remains energized when a train moving into siding g from section B—C, or vice versa, 80 de-energizes relay P'. It follows that under this condition, that is, when circuit controller 251 is reversed, the presence of a train in section B—C does not prevent traffic movements along track d over the crossing. 85

If a train enters section B—C from siding g, and it is desired to move the train over crossing 2, circuit controller 288 is closed. This energizes relay t¹⁵. The energization of relay t¹⁵ opens, at back contact 282 thereon, the stick circuit for relay t' which thereupon becomes de-energized. Relay f is thus de-energized, thus preventing clearing of all conflicting signals, and signal S^c is moved to the proceed position as soon as switch 270 100 is returned to its normal position to close circuit controller 252.

It should be pointed out that if switch 270 is moved to the normal position to permit a train to enter section B—C from siding g, 105 and such train continues to move westward, this does not cause trains approaching the crossing over track d to be stopped.

Although I have herein shown and described only two forms of apparatus embodying my invention, it is understood that various changes and modifications may be made therein within the scope of the appended claims without departing from the spirit and scope of my invention. 110

Having thus described my invention, what I claim is:

1. In combination, two intersecting railway tracks, traffic governing apparatus for at least one of said tracks controlled by traffic conditions on said one track and capable of assuming a more and a less restrictive condition, and means for changing such apparatus to or holding it in the more restrictive condition when a train moving in one direction 120 and approaching the crossing on the other track is at a comparatively long distance therefrom and for releasing said apparatus when a train moving in the opposite direction and receding from the crossing on such 125 130

- other track is at a comparatively short distance therefrom.
2. In combination, two intersecting railway tracks, four signals one for governing traffic approaching the intersection from each direction, four relays one controlled by each of said signals, and an operating circuit for each signal controlled by the the relays associated with the other three signals.
3. In combination, two intersecting railway tracks, four signals one for governing traffic approaching the intersection from each direction, a relay for each signal arranged to be energized only when the associated signal indicates stop, and an operating circuit for each signal controlled by the relays associated with each of the other signals.
4. In combination, two intersecting railway tracks, a relay, a signal for governing traffic over one said track, means for causing said signal to display a proceed indication only when said relay is energized, a second signal for governing traffic over the other track, means for causing said second signal to display a proceed signal only when said relay is de-energized, and means for controlling said relay in response to traffic conditions in said tracks.
5. In combination, two intersecting railway tracks, a relay, a signal for governing traffic over one said track, means for causing said signal to display a proceed indication only when said relay is energized, a second signal for governing traffic over the other track, means for causing said second signal to display a proceed signal only when said relay is de-energized, and means for controlling said relay in response to traffic conditions in said tracks and in accordance with the direction of traffic over said tracks.
6. In combination, two intersecting railway tracks, a normally energized relay, means for de-energizing said relay when a train approaching the intersection from either direction on one track is at a comparatively long distance from the intersection and for re-energizing the relay when such train is receding from the intersection in either direction at a comparatively short distance from the crossing on said one track, and means controlled by said relay for governing traffic over the other track.
7. In combination, two intersecting railway tracks, a normally energized relay, means for de-energizing said relay when a train approaching the intersection on one track from either direction is at a comparatively long distance from the intersection and for re-energizing the relay when such train is receding from the intersection in either direction on said one track at a comparatively short distance from the crossing, and means for preventing trains on the other track from approaching the crossing when said relay is de-energized.
8. In combination, two intersecting rail-
- way tracks, a normally energized relay, means for de-energizing said relay when a train approaching the intersection from either direction on one track is at a comparatively long distance from the intersection and for re-energizing the relay when such train is receding from the intersection in either direction at a comparatively short distance from the crossing on said one track, signals for governing traffic through said intersection over the other track in both directions, and means for clearing said signals only when said relay is energized.
9. In combination, two intersecting railway tracks, a normally energized relay, means for de-energizing said relay when a train approaching the intersection from either direction on one track is at a comparatively long distance from the intersection and for re-energizing the relay when such train is receding from the intersection in either direction at a comparatively short distance from the crossing on said one track, signals for governing traffic through said intersection over the other track in both directions, and means for clearing said signals for traffic movements in one direction only at a time and then only when said relay is energized.
10. In combination, two intersecting railway tracks, a normally energized relay, means for de-energizing said relay when a train approaching the intersection from either direction on one track is at a comparatively long distance from the intersection and for re-energizing the relay when such train is receding from the intersection in either direction at a comparatively short distance from the crossing on said one track, signals for governing traffic through said intersection over the other track in both directions, means for energizing certain of said signals when a train approaches said intersection on said other track provided said relay is energized.
11. In combination, two intersecting railway tracks, a normally energized relay, means for de-energizing said relay when a train approaching the intersection from either direction on one track is at a comparatively long distance from the intersection and for re-energizing the relay when such track is receding from the intersection in either direction at a comparatively short distance from the crossing on said one track, signals for governing traffic through said intersection over the other track in both directions, means for energizing such signal for governing traffic in one direction when a train approaches the intersection moving in such direction provided said relay is energized.
12. In combination, two intersecting railway tracks, a normally energized relay, means for de-energizing said relay when a train approaching the intersection from either direction on one track is at a comparatively long distance from the intersection and for re-en-

ergizing the relay when such train receding from the intersection in either direction is at a comparatively short distance from the crossing on said one track, and means controlled by said relay for governing traffic over both said tracks.

13. In combination, two intersecting railway tracks, a normally energized relay, means for de-energizing said relay when a train approaching the intersection from either direction on one track is at a comparatively long distance from the intersection and for re-energizing the relay when such train is receding from the intersection in either direction at a comparatively short distance from the crossing on said one track, a signal for governing traffic over said one track, means for clearing said signal when said relay is de-energized, and means for preventing the de-energization of said relay by a train on said one track if a train is approaching said intersection over the other track.

14. In combination, two intersecting railway tracks, a normally energized relay, means for de-energizing said relay when a train approaching the intersection from either direction on one track is at a comparatively long distance from the intersection and for re-energizing the relay when such train is receding from the intersection in either direction at a comparatively short distance from the crossing on said one track, a signal for governing traffic over said one track, means for clearing said signal when said relay is de-energized, and means for preventing the de-energization of said relay by a train on said one track if a train is approaching said intersection over the other track.

15. In combination, two intersecting railway tracks, a normally energized relay, means for de-energizing said relay when a train approaching the intersection from either direction on one track is at a comparatively long distance from the intersection and for re-energizing the relay when such train is receding from the intersection in either direction at a comparatively short distance from the crossing on said one track, two signals one for governing traffic in each direction over said one track, means for clearing one or the other of said signals when said relay is de-energized and a train is approaching the intersection over said one track, and means for preventing the de-energization of said relay when a train is approaching said intersection over the other track.

16. In combination, two intersecting railway tracks, a siding for the first said track adjacent the intersection of said tracks and provided with a switch, two signals normally indicating stop and one for governing traffic in each direction through said intersection over the second track, a relay normally energized but arranged to be de-energized when a train approaches said intersection over said

first track, means for at times preventing such de-energization of the relay when said switch is in a position to permit traffic movements from said first track into said siding, and means controlled by said relay for at 70 times causing said signal to indicate proceed.

17. In combination, two intersecting railway tracks, a siding for the first said track adjacent the intersection of said tracks and provided with a switch, two signals normally 75 indicating stop and one for governing traffic in each direction through said intersection over the second track, a relay normally energized but arranged to be de-energized when a train approaches said intersection over said first track, means for at times preventing such deenergization of the relay when said switch is in a position to permit traffic moves from said first track into said siding, and means effective when a train approaches said intersection over said second track and controlled by said relay for causing one or the other of said signals to indicate proceed depending upon the direction in which such train is moving.

18. In combination, two intersecting railway tracks, a siding for the first said track adjacent the intersection of said tracks and provided with a switch, two signals normally indicating stop and one for governing traffic in each direction through said intersection over the second track, a relay normally energized but arranged to be de-energized when a train approaches said intersection over said first track, means for at times preventing such de-energization of the relay when said switch is in a position to permit traffic moves from said first track into said siding, and means effective when a train approaches said intersection over said second track and said relay is energized for causing one or the other of said signals to indicate proceed.

19. In combination, two intersecting railway tracks, a siding for the first said track adjacent the intersection of said tracks and provided with a switch, two signals normally indicating stop and one for governing traffic in each direction through said intersection over the second track, a relay normally energized but arranged to be de-energized 110 when a train approaches said intersection over said first track, means for preventing such de-energization of the relay when a train is approaching said intersection over said first track in one direction and said switch is in such position as to permit movement of traffic from said first track into said siding, and means effective when a train approaches said intersection over said second track and said relay is energized for causing one or the other of said signals to indicate proceed.

In testimony whereof I affix my signature.

HENRY S. YOUNG.
